CLAIM

The ornamental design for a display screen or portion thereof with graphical user interface, as shown and described.

DESCRIPTION

FIG. 1 is a front view of a first embodiment of a display screen or portion thereof with graphical user interface, showing our new design; and,

FIG. 2 is a front view of a second embodiment of a display screen or portion thereof with graphical user interface, showing our new design.

The outermost broken lines illustrating portions of a display screen or portion thereof in FIGS. 1-2 form no part of the

(Continued)

claimed design. The remainder of the broken lines illustrating portions of the graphical user interface forms no part of the claimed design.
